FUEL CONTROL MEANS

Harry C. Shagaloff, Evansville, Ind., assignor, by
mesne assignments, to Servel, Inc., Dover, Del.,
a corporation of Delaware

Application August 21, 1934, Serial No. 740,757

3 Claims. (Cl. 158—38)

My invention relates to refrigeration and more particularly to a refrigerator of the absorption type operated by a liquid fuel burner.

It is an object of my invention to provide a refrigerator of this type having automatic thermostatic control.

Another object is to provide an absorption type refrigerator having a float regulated liquid fuel burner to which the supply of liquid fuel is controlled responsive to the refrigeration temperature.

A further object is to provide an absorption type refrigerator having a thermostatically controlled liquid fuel burner adapted to maintain a minimum or pilot flame.

A still further object of my invention is to provide a thermostatically controlled liquid fuel burner for an absorption type refrigerator which is not subject to smoking upon sudden changes in the thermostat temperature or adjustment.

In a liquid fuel burner with a float regulated liquid level there is an appreciable amount of liquid fuel normally contained in the float chamber. It is, therefore, a characteristic of such a burner that the flame slowly diminishes as the liquid level decreases when the fuel supply is shut off. In accordance with my invention, I provide an absorption type refrigerator heated by a float regulated liquid fuel burner and, to automatically control the refrigeration temperature, utilize a thermostatically operated valve in the fuel line to the burner, and take advantage of the natural holdover of the burner to keep it ignited while the thermostatic valve is closed.

Two principal problems are presented in securing satisfactory burner operation with such automatic control. When the control valve is closed for an appreciable length of time and the surface level of liquid fuel in the burner decreases, the burner flame becomes unstable and may become extinguished. I meet this problem by providing a wick extending downwardly below the level of liquid in the burner to maintain a flame upon decrease in liquid level. The length of time that a flame will be maintained by this wick is determined by the volumetric capacity of the burner which may be increased, for instance, by increasing the size of the float chamber. By this means, a minimum flame is maintained for automatically relighting the burner when the automatic valve is opened and the supply of liquid to the burner resumed. The wall of the burner receptacle in which vaporization of the liquid fuel occurs becomes heated above the level of liquid fuel due to combustion of the vapor when mixed

with air. As the level of liquid fuel in this receptacle decreases upon closing of the automatic control valve, the wall of the receptacle becomes heated to a greater degree. If the liquid level should be rapidly increased, as upon rapid operation of the automatic control device, excessive vaporization of liquid fuel occurs due to the rapid contact of the liquid with the hot wall of the receptacle. This excessive vaporization is evidenced by an undesirable smoking of the burner which is due to incomplete combustion of the excess vapor. I therefore provide a liquid flow restricting means in the fuel line to the burner, for instance a capillary tube, to dampen a surge or rapid flow of liquid in the burner upon rapid operation or adjustment of the automatic control device.

My invention will be more fully understood upon reference to the following description and the accompanying drawings forming part of this specification and of which:

Fig. 1 is a broken side elevation, with parts broken away, of a refrigerator embodying my invention;

Fig. 2 is a detail view, partly in vertical section, of a liquid fuel burner and control device for the refrigerator shown in Fig. 1;

Fig. 3 is a detail section on line 3—3 in Fig. 2;

Fig. 4 is a detail section illustrating a modification of the apparatus illustrated in the other figures; and

Fig. 5 is a detail section on line 5—5 in Fig. 2.

Referring to Fig. 1 of the drawings, a refrigerator cabinet 10 includes a thermally insulated storage compartment 11 accessible by means of a door 12, and a lower apparatus compartment 13 accessible by means of a downwardly hinged door 14. An absorption refrigeration apparatus is mounted in the cabinet 10 and includes a cooling element or evaporator 15 in the upper part of the insulated storage compartment 11, and a generator having a substantially horizontal portion 16 in one side of the lower apparatus compartment 13. The horizontal portion 16 of the generator is provided with a substantially horizontal inner heating flue 17 extending therethrough and is surrounded by an outer heating flue 18. The outer heating flue 18 is surrounded by suitable thermal insulating material 19, such as mineral wool, retained in place by a light sheet metal casing 20. The forward end of the heating flue 18 projects beyond the front end of the casing 20 and also beyond the end of the inner flue 17. Beneath the projecting end of the outer heating flue 18 is mounted a liquid fuel burner assembly 21 having

a removable chimney or combustion shield 22 which extends upwardly into the forwardly projecting end of the outer heating flue 18 which is provided with a cutaway portion or recess 23 to admit the upper end of the chimney 22. The forwardly projecting end of the flue 18 and the upper end of the burner chimney 22 are enclosed by a removable thermally insulated hood 24. For a more complete description of this assembly, reference may be had to an application Serial No. 734,075, of William R. Hainsworth.

In the other side of the lower apparatus compartment 13 is a storage tank or reservoir 25 for liquid fuel, such as kerosene. In accordance with my invention, liquid is conducted from the reservoir 25 to the burner 21 through a conduit 26, a thermostatically operated valve 27, and a conduit 28. The thermostat for operating the valve 27 is preferably of the expansible fluid type and includes a sensitive bulb 29 located in thermal exchange relation with the evaporator or cooling element 15 or the space to be cooled and connected to the thermostatic valve 27 by a small tube 30.

The path of liquid flow from the reservoir to the burner may be better understood by reference to Figs. 2 and 3. In Fig. 2 there is shown, in vertical section, only that part of the burner necessary for explanation of my invention. The burner and safety valve 31 are disclosed in more complete detail in said application Serial No. 734,075 of William R. Hainsworth. The liquid fuel supply line 26 from the reservoir is connected to the thermostatically operated valve 27, shown in section in Fig. 3. The thermostatic valve 27, as illustrated, comprises a substantially cylindrical body member 32 having a central partition 33 forming chambers 34 and 35. A valve opening 36 in the partition 33 affords communication between the chambers 34 and 35. The chamber 34 is closed by a cover 37 and the chamber 35 is closed by a resilient diaphragm 38, secured at its periphery between the body 32 of the valve casing and a cover 39. A valve member 40 in chamber 34 is adapted to cooperate with the valve opening 36 to control flow of liquid through the latter and is operatively connected by a valve stem 41, extending through the valve opening 36, to an expansible element such as a bellows 42 in the chamber 35 and mounted on the diaphragm 38. The bellows 42 is connected by means of the small tube 30 to the sensitive bulb 29 on the refrigerator cooling element, the bellows 42, tube 30, and bulb 29 forming an expansible fluid thermostat for operating the valve member 40 to control flow of liquid fuel through the valve opening 36 responsive to temperature of the refrigerator cooling element. The thermostat is adjustable by means of a screw 43 threaded through the cover 39 into adjustable abutment against the resilient diaphragm 38 on which the thermostat bellows 42 is mounted.

Liquid fuel flows from the reservoir 25 through the supply conduit 26 into the chamber 34, and flow of liquid from the chamber 34 through the passage 36 into the chamber 35 is controlled by the valve member 40. From the valve chamber 35, liquid fuel flows through the conduit 28 to a normally open safety valve 31. The latter is adapted to be closed upon overflow of liquid from the burner or hazardous increase in temperature outside of the burner as described in said application of William R. Hainsworth. After passage through the safety valve 31, the liquid flows through a conduit 44 to a chamber 45.

Communication between the chamber 45 and a float chamber 46 of the burner is controlled by a float operated valve 47. In Fig. 2, there appears only a portion of the float chamber 46, which is shown more fully in vertical section in Fig. 5. Communication between the float chamber 46 and a chamber 48 is controlled by a manually adjustable valve 49. The lower end of a burner tube 50 is connected to the chamber 48, and the upper end of the burner tube 50 is connected to the lower part of an annular burner well 51. Above the burner well 51 is removably located the burner chimney or combustion shield assembly 22, comprising perforated cylinders 53 and 54 surrounded by an imperforate frustoconical shield or chimney 55, the cylinders 53 and 54 and the shield 55 being concentrically located in spaced relation with respect to each other and secured by mutually perpendicular bars 56 and 57 which extend through the concentric elements 20 and are retained in position by pins 58 in the outer ends thereof.

Flow of liquid fuel from chamber 45 into the float chamber 46 is regulated by the float valve 47. As may be seen in Fig. 5, the float chamber 46 includes an elongated passage connecting two float vessels 63 and 64. In the latter are floats 65 and 66 from which is suspended a beam 67 located in the elongated passage. The valve 47 is connected to the center of the beam 67 so as to be operated by the floats 65 and 66 to cut off flow of kerosene into the float chamber at a desired liquid level which is thus maintained substantially constant. If, for any reason, this liquid level in the float chamber should rise, liquid would overflow through conduit 62 and cause operation of the safety valve 31 to cut off further supply of liquid to the burner. From the float chamber 46, liquid flows past the manually adjustable valve 49 into the chamber 48 and the burner tube 50. When the burner is lighted, kerosene flows past the valve 49 at a rate dependent upon the setting of this valve. The maximum level of liquid in the burner tube 50 and, therefore, the maximum burner flame depends upon the rate of flow past the valve 49. The valve 49 may therefore be referred to as a maximum flame adjustment valve. It will be understood that the valve 49 may be closed to isolate the burner tube 50 and well 51 from the float chamber 46.

During operation of the refrigerator, that is, when the burner is lighted, flow of liquid to the burner is controlled by the thermostatic valve 27 responsive to temperature of the refrigerator cooling element 15, as previously described. This thermostatic operation of valve 27 affects the size of the burner flame, within the maximum limit determined by the float valve 47 and manual valve 49, to maintain the temperature of the cooling element 15 substantially constant. If the temperature of the cooling element 15 decreases sufficiently to entirely close the thermostatic valve 27, the burner flame gradually decreases as the liquid level in the float chamber 46 and burner tube 50 gradually decreases. In order to increase the time that the thermostatic valve 27 may remain closed without causing the burner flame to go out, I provide a wick 59 extending from the burner well 51 downwardly into the burner tube 70 50 so that a flame will be maintained by supply of liquid fuel through the wick as long as the level is above the lower end of the wick. It will be understood that the wick 59 should not obstruct the normal flow of liquid upwardly in the 75

burner tube 50. In Fig. 4, I have shown a slight modification in which a separate tube 60 is connected from the burner well 51 to the lower part of the burner tube 50 and contains a wick 61 which need not extend into the burner tube 50, and therefore does not interfere with flow of liquid in the burner tube.

During operation with a minimum flame, the upper end of the tube 50 and the well 51 of the burner become exceedingly heated, and, if liquid is suddenly admitted to the burner after such minimum flame operation, vaporization of liquid in the burner tube 50 and burner well 51 is so rapid that incomplete combustion occurs in the chimney 22, which is evidenced by smoke. Such surge of liquid into the burner might be caused by rapid operation or adjustment of the thermostatic valve 27. After the thermostatic valve 27 has been closed for an appreciable length of time, the regulating or float operated valve 47 is open wide, and sudden flow of liquid will cause rapid rise of liquid in the burner tube before being checked by closing of the float valve. In order to minimize such liquid surge into the burner and the resultant smoking, I provide a liquid flow restricting means in the kerosene supply line to the burner, for instance, by forming conduit 28 with a small internal diameter. Conduit 28 is preferably made small enough to be referred to as a capillary tube. It will be understood that other liquid flow restricting means may be used which permit sufficient flow for high flame so that a limitation is not placed on flow through valve 49 but which, when the thermostatically operated valve is opened, prevent rapid rise of liquid level in the float chamber to restrict the head differential between liquid in the float chamber and liquid at the wick. In such an arrangement, pulsations in the flow of liquid to the burner, which may be caused by the rapid operation or adjustment of the thermostatic control valve 27, are damped by the flow restriction.

Other changes and modifications will be apparent to those skilled in the art wherefore my invention is not limited to that which is shown in the drawings and described in the specification but only as indicated in the following claims.

What I claim is:

1. A liquid fuel burner including a float chamber, a burner well, means including a vertically extending tube having its upper and lower ends communicating with said burner well and float chamber, respectively, a reservoir for liquid fuel, a conduit for conducting liquid from said reservoir, a valve in said conduit, means including a thermostat for operating said valve, means connecting said conduit to said float chamber to provide the only passage for conducting liquid fuel to the latter and including a capillary passage for preventing liquid surge upon operation of said valve, a float operated valve for controlling admission of liquid fuel to said float

chamber responsive to level of liquid in the latter, and a wick in said burner well having at least a portion thereof in the path of flow of liquid in said tube for maintaining a flame upon decrease in level of liquid in the latter.

2. A liquid fuel burner comprising a burner well, a float chamber, a first flow passage communicating with said burner well and float chamber, respectively, for conducting liquid fuel from said float chamber to said burner well and including a vertically extending tube having its upper end communicating with said burner well, a second flow passage including a conduit for conducting liquid fuel from a source of supply to said float chamber, a valve in said conduit, means including a thermostat for controlling said valve, the portion of said conduit between said valve and said float chamber providing the only passage for conducting liquid fuel to the latter, a float operated valve responsive to the level of liquid fuel in said float chamber for controlling the admission of liquid fuel into the latter, a float in said float chamber for actuating said float operated valve, a wick in said burner well having at least a portion thereof in the path of flow of liquid fuel in said tube for maintaining the flame after a drop in the level of the liquid fuel in said burner well, said float and float chamber being constructed and arranged to provide a head of liquid fuel affecting flow to the burner well, and flow restricting means in said second passage constructed and arranged to allow flow for high flame and, when the thermostatically operated valve is opened, to prevent rapid rise of liquid level in the float chamber to restrict the head differential between liquid in the float chamber and liquid at the wick.

3. A liquid fuel burner comprising a burner well, a float chamber, means including a vertically extending tube having its upper and lower ends communicating with said burner well and float chamber, respectively, said tube providing a passage for conducting liquid fuel from said float chamber to said burner well, means including a conduit for conducting liquid fuel from a source of supply to said float chamber, a valve in said conduit, means including a thermostat for controlling said valve, the portion of said conduit between said valve and said float chamber providing the only passage for conducting fuel to the latter and including a capillary passage for dampening pulsations in the flow of liquid fuel therethrough, a float operated valve responsive to the level of liquid fuel in said float chamber for controlling the admission of liquid fuel into the latter, and a wick in said burner well extending downwardly in said tube for maintaining the flame after a drop in the level of liquid fuel in said tube, said wick being of such size that the normal flow of liquid fuel through said tube is not obstructed.

HARRY C. SHAGALOFF.
